UNITED STATES PATENT OFFICE.

ELMER HYSSELL, OF COLLEGE HILL, PENNSYLVANIA, ASSIGNOR OF ONE-HALF TO
CYRUS E. RUBLE, OF ROCHESTER, PENNSYLVANIA.

SADIRON.

1,400,437.

Specification of Letters Patent. Patented Dec. 13, 1921.

Application filed March 24, 1921. Serial No. 455,278.

To all whom it may concern:

Be it known that I, ELMER HYSSELL, residing at College Hill, in the county of Beaver and State of Pennsylvania, a citizen of the 5 United States, have invented or discovered certain new and useful Improvements in Sadirons, of which improvements the following is a specification.

My invention relates to improvements in 10 sad irons, and the object in view is found in certain advantages in conditions of use.

The invention is illustrated in the accompanying drawings. Figure I is a view partly in side elevation partly in vertical 15 section of a sad iron of my invention in such position on its stand as ordinarily it takes when in service; Fig. II is a plan view of the stand from above; Fig. III is a view in section through the stand on a plane immediately beneath the top plate; and Fig. 20 IV is a fragmentary view, partly in elevation, partly in section, showing the iron in such position on the stand as it initially may occupy, when use is about to begin.

25 The iron itself is indicated by the numeral 1, the stand by the numeral 2; 3 is a plug, through which connection is made to a source of electrical energy, ordinarily a domestic service line. Both iron and stand 30 are, it will be observed, connected with plug 3 through cables 5 and 6. The wiring and contacts are such that the two members, iron and stand, are connected in series with the source of energy. Within the iron itself 35 is a heat-generating member, indicated at 4 in the familiar form of a resistance coil. Within the stand is a make-and-break device. This make-and-break device consists of contact pieces, 7, 7 and 8, 9, one of which at 40 least is movable to and from contact with its fellow. In this illustration the two contact pieces 8, 8 are carried on a block 9 of insulating material, being connected one with another through a wire 10 also borne 45 by the block 9. Block 9 is pivoted (cf. Figs. III and IV) in the frame of the stand.

Normally block 9 is swung under the tension of a spring 11 to bring contact pieces 50 8 into contact with and maintain them in contact with the contact pieces, 7, 7. From block 9 a crank arm 12 rises through the top plate 13 of the stand; and the position and arrangement are such that when the iron 55 is brought to its seat on the stand, the weight of the iron rests primarily on the free end

of the crank arm 12. By the weight of the iron, the crank arm is depressed until the iron comes firmly to its seat upon top plate 13, but the depression is sufficient to turn block 9 on its pivot, against the tension of 60 spring 11, and to break the contact between plates 8, 8 and 7, 7. Fig. 1 shows the iron in its seat on the stand, and the make-and-break device open.

Advantageously the top plate of the stand, 65 which in shape and size conforms to the iron, is of conventional shape and the iron is of conventional shape, elongate and pointed. About the rim of top plate 13 of the stand is raised a rim 14. It rises substantially as 70 high as or higher than the rise of the end of crank arm 12 through the top plate 13. Conveniently it is formed of rather heavy wire, about which are rolled the edges of the sheet of metal out of which the top plate is 75 in the main formed. Fig. I shows the iron seated in the stand, and when so seated holding by its weight the make-and-break device open; Fig. IV shows the iron applied to the stand transversely, resting not on the web 80 of the top plate 13, but on the marginal flange 14. In this position the iron is not effective to depress crank arm 12, at least not sufficiently to open the make and break device.

85 The operation will be manifest. Normally, stand and iron being separated the make-and-break device within the stand is closed. When the iron is to be used, plug 3 is inserted in the socket prepared for it. 80 The initial desideratum is that the iron shall become heated to the degree necessary for service; and it is advantageous that while becoming so heated it may rest where, even though neglected, its heat may do no harm. 85 Accordingly, initially the iron may be placed transversely on the stand, in the position indicated in Fig. IV. With the iron in this position there is no interruption of current flow; the heating element within the 100 iron is active, and the temperature of the iron thus comes to the desired degree. Even though that degree be exceeded and even though the iron be neglected for a time, no damage can be caused. When the user comes 105 to apply the iron he raises it from the stand. If it be too hot, he need only seat it on the stand again, in the fully seated position illustrated in Fig. I; the heating current will then cease to flow and the excess heat will be 110

dissipated. During use, the iron will constantly be heated; if at any time it grows too hot, it may be seated in the stand to cool. When not in use it may be seated and the current will automatically be cut off and waste prevented. When the iron is to be used again it is necessary only to pick it up (and, if desired, to rest it again transversely upon the stand), when shortly it will become heated.

Manifestly details of structure may be varied widely, within the knowledge of an engineer.

I claim as my invention:

- 15 1. A sad-iron structure including iron and stand adapted to be connected in series with a source of electric current, a heating element within the iron, and a make-and-break device in the line of current flow opened by the seating of the iron in the stand, whereby flow from the source of current through iron and stand is cut off, and closed by the removal of the iron from such seating, whereby the flow from the source of current through iron and stand is established.
- 20 2. A sad-iron structure including iron and

stand adapted to be connected in series with a source of electric current, a heating element within the iron, and a make-and-break device in the line of flow of current, said stand being adapted to sustain the iron in either of two positions, and the make-and-break device being arranged to be swung by the weight of the iron when applied in one but not in the other of its two positions to the stand.

3. A sad-iron structure including iron and stand adapted to be connected in series with a source of electric current, a heating element within the iron, a make-and-break device within the stand, the said stand being provided with a seat including a medial web and a marginal flange standing above the plane of the web, and a make-and-break device operating member rising through the web of the seat.

In testimony whereof I have hereunto set my hand.

ELMER HYSSELL.
